UNITED STATES PATENT OFFICE

2,152,249

WINDOW VENTILATOR

Michael A. Galgoczy, Jr., Cleveland, Ohio, assignor of one-fourth to Frank Bucsi, Cleveland, Ohio

Application February 1, 1938, Serial No. 188,150

3 Claims. (Cl. 98—44)

My invention relates to improvements in window ventilators of the type adapted to be interposed between the window sash and window sill and the principal object of the invention is to provide a ventilator of the type indicated equipped to trap breezes blowing across the window from opposite directions and to deflect the same inwardly of said window.

Other objects of the invention are to provide a device of the character and for the purpose above set forth which may be readily applied, and removed, is strong and durable, light in weight, and inexpensive to manufacture.

To the accomplishment of the above and subordinate objects presently appearing a preferred embodiment of my invention has been illustrated in the accompanying drawings, treated in detail in the succeeding description and defined in the claims appended hereto.

20 In said drawings:

Figure 1 is a view in horizontal transverse section of a window equipped according to my invention.

Figure 2 is a detail view in vertical transverse section taken on the line 2—2 of Figure 1 looking in the direction indicated by the arrows and drawn to an enlarged scale.

Figure 3 is a view in vertical transverse section taken on the line 3—3 of Figure 1 looking in the direction indicated by the arrows.

Figure 4 is a view in horizontal section taken on the line 4—4 of Figure 3 looking downwardly, and

Figure 5 is a fragmentary view in side elevation of one of the clips and bails the purpose of which will presently appear.

Referring to the drawings by numerals, the device of my invention comprises an extensible window screen 1 having a pair of laterally sliding overlapping sections 2 and 3 adapted to be interposed between the lower sash 4 of the window 5 and the window-sill 6, and an adjustable deflector unit 7 extending outwardly from said screen 1 centrally thereof and beyond the window.

45 The deflector unit 7 comprises a rectangular upstanding baffle plate 8 of light flexible metal, such as sheet tin, secured at one end, in a manner presently described, to the edges of the screen 1 and of a width coinciding substantially with the height of the screen 1, and a length to extend well out beyond the window casing 9.

50 Secured at its rear edge to the baffle plate 8, as by soldering, not shown, is a second shorter baffle plate 10 of a similar material extending

alongside approximately the outer half of the plate 8. From the point of connection on plate 10 the plate 8 has its upper edge and also its lower edge bent or crimped, as at 11 and 12, to reinforce the inner half of the said plate 8 against lateral bending or flexing. The outer half of said plate 8 and the plate 10 are free to be flexed or bent laterally in opposite directions into separated relation to form concave deflectors functioning in conjunction with the inner half of the plate 8 to trap breezes, or air currents, blowing across the window in opposite directions and deflect the same inwardly of the window 5.

The described deflector unit 7 is secured to the screen 1 as follows. The rear edge of the plate 8 is bent upon itself to form a vertically extending socket 13 along said edge of rectangular cross section. A pair of upper and lower right-angled metal brackets 14 and 15 are interposed between the upper edge of the screen 1 and the sash 4, 20 on the one hand, and between the lower edge of said screen and the window sill 6 on the other hand, said brackets fitting around the edges of the screen 1 adjacent the inner ends of the sections 2 and 3, and having right-angled ends 16 25 fitting into the upper and lower ends of said socket respectively. The upper bracket 14 has an upstanding extension 17 adapted to bear against the inner face of the sash 4 to hold the top edge of the screen 1 against displacement outwardly. 30 A set screw 18 in the upper bracket 14 adapted to be turned against the inner side of the screen 1 provides for securing the unit in a vertical upstanding position.

35 The outer half of the plate 8 and the plate 10 are held in laterally bent position by the following means. A pair of U-shaped clips 19 are slidably mounted on the top edge of the screen 1 to straddle the same for adjustment along the 40 outer ends of the sections 2 and 3, respectively, into different set positions established by a set screw 20 extending from the inner side of each clip 19 and adapted to bear against the appropriate sections. A pair of V-shaped rodlike bails 45 having upper and lower arms 22 are suitably mounted at the closed ends thereof, as at 23, on the clips 19, respectively, for lateral swinging movement. The free ends of the arms 22 of one bail are pivotally connected to the plate 8 adjacent the upper and lower edges thereof and contiguous the outer end of said plate, and the free ends of the other bail are similarly connected to the plate 10. Preferably the connection of the arms 22 to the plates 8 and 10 takes the form of 50 55

sleevelike ears 24 suitably secured to said plates, the arms 22 being bent as at 25, to extend into said ears.

As will be clear, by shifting the clips 19 along the screen 1 into different set positions, the outer half of plate 8 and plate 10 may be flexed into different curvatures or permitted to react into substantially straight positions as occasion may require. The outer half of plate 8 and the plate 10 are provided with vertically extending louvres 26 whereby wind blowing directly against the outer sides thereof may pass there-through.

As indicated by the arrows in Figure 1 the described invention provides for trapping and deflecting breeze or air currents blowing across the window from the right-hand side thereof, so that air is caused to enter the window on one side of the deflector unit, while air currents blowing across said window from the left-hand side thereof are similarly caused to enter the window on the left-hand side of said deflector unit and air blowing directly into the window is in no way blocked by said deflector unit.

The foregoing will, it is believed, suffice to impart a clear understanding of the construction, operation and advantages of my invention without further explanation.

Manifestly, the invention as described, is susceptible of modification without departing from the inventive concept, and right is herein reserved to such modifications as fall within the scope of the subjoined claims.

What I claim is—

1. A ventilator device for windows comprising a screen, a deflector unit extending from one side of the screen centrally thereof comprising a

pair of baffle plates of flexible reactive material secured together side by side for flexing laterally into oppositely curved separated relation, and means for flexing said plates into different set positions.

2. A ventilator device for windows comprising a screen, a deflector unit extending from one side of the screen centrally thereof comprising a pair of baffle plates of flexible reactive material secured together side by side for flexing laterally into oppositely curved separated relation, and means for flexing said plates into different set positions, comprising a pair of clips slidably mounted on the upper edge of said screen, and rodlike connections extending between said plates and clips and pivoted thereto.

3. A ventilator device for windows comprising a screen, a rectangular plate-like deflector unit adapted to be secured at one end to said screen to extend from one side thereof centrally of the same and having at the opposite end thereof a pair of baffle portions of flexible material disposed side by side for flexing laterally into oppositely curved separated relation, means for securing the unit to said screen comprising a pair of angle brackets fitting around the upper and lower edges of said screen and provided with anchoring devices secured to the first-mentioned end of said unit, and means for flexing said baffle portions into different set positions comprising a pair of clips slidably mounted on the upper edge of said screen, and rodlike connections extending between said portions and clips and pivoted thereto.

MICHAEL A. GALGOCZY, JR.
